United States Patent Office

Des. 189,527
Patented Jan. 3, 1961

189,527

RAILING POST

Louis Blum, Pittsburgh, Pa., assignor to Blumcraft of
Pittsburgh, Pittsburgh, Pa., a firm

Filed Dec. 29, 1958, Ser. No. 53,938

Term of patent 14 years

(Cl. D13—7)

FIG. 1

FIG. 2

FIG. 3

FIG. 4.

Fig. 1 is a front elevational view of a railing post embodying my new design;

Fig. 2 is a side elevational view thereof;

Fig. 3 is a top plan view thereof; and

Fig. 4 is an enlarged front perspective view of a portion of the post shown in Fig. 1.

I claim:

The ornamental design for a railing post, as shown.
